UNITED STATES PATENT OFFICE.

FLORA J. McACHRAN, OF BLOOMFIELD, IOWA.

HATCHWAY-GUARD.

1,255,621.

Specification of Letters Patent. Patented Feb. 5, 1918.

Application filed August 29, 1917. Serial No. 188,833.

To all whom it may concern:

Be it known that I, FLORA J. McACHRAN, a citizen of the United States, residing at Bloomfield, in the county of Davis and 5 State of Iowa, have invented certain new and useful Improvements in Hatchway-Guards, of which the following is a specification.

This invention relates to an improved 10 guard for use in connection with a hatchway and the principal object of the invention is to provide a guard which may be connected with a door or closure for the entrance to a side-walk door, it being of course understood that the guard could be 15 used in connection with the closure for any similar opening in a floor of a building.

Another object of the invention is to so 20 construct this guard that when the door or closure is raised, the guard will swing to an open position, the guard being limited in its swinging movement by an abutment arm and serving not only as a guard but further serving as means for retaining the 25 closure in a raised position.

This invention is illustrated in the accompanying drawings, wherein—

Figure 1 is a perspective view showing a 30 hatchway door raised and the guard moved to the operative position, and,

Fig. 2 is a fragmentary view looking toward the inner face of the guard.

The closure or door 10 for the hatchway 11 formed in the side-walk, flooring or other structure 12 may be hingedly mounted as 35 shown in Fig. 1 so that the door may be swung upwardly to the open position shown. The guard comprises the two leaves or sections 13 and 14 which will be hingedly connected to the door 10 and to each other by 40 spring hinges 15 and when the door is closed will be positioned as indicated by dotted lines in Fig. 1. When the door is raised, the spring hinges will cause the 45 leaves or sections to swing outwardly to the position shown and this guard will then rest upon the flooring or side-walk about the end portion of the hatchway. In order 50 to prevent the guard from swinging outwardly beyond the desired amount, there has been provided an abutment arm 16 engaging the wall of the hatchway and effectively serving to prevent both sections from

swinging outwardly beyond the desired amount. Any conventional form of latch 55 may be provided to retain the guard in folded position indicated by dotted lines in Fig. 1.

In the accompanying drawing, a guard 60 has been shown applied to one end of the door 10 but it is obvious that if desired, a similar guard could be provided at the opposite end of the door thus protecting both ends of the hatchway.

What is claimed is—

1. A structure having a hatchway provided therein, a closure for the hatchway, and a guard for the hatchway comprising a leaf hingedly connected with the closure for swinging outwardly, a second leaf hingedly 70 connected with the outer end of the first mentioned leaf, and an abutment arm carried by the second leaf adjacent its pivoted end for fitting into the hatchway and engaging the wall thereof to limit the outward swinging movement of the guard. 75

2. A structure having a hatchway formed therein, a closure for the hatchway, and a guard for the hatchway comprising a leaf hingedly connected with the closure for 80 swinging outwardly and extending along one end of the hatchway, a second leaf hingedly connected with the first mentioned leaf for swinging outwardly and extending along one side of the hatchway, and an 85 abutment arm carried by one leaf for limiting the outward swinging movement of the leaves.

3. A structure having a hatchway formed therein, a closure for the hatchway, and a 90 guard for the hatchway comprising a section hingedly connected with the closure for swinging outwardly along one end of the hatchway, and a second section hingedly connected with the first mentioned section 95 for swinging outwardly and extending along one side of the hatchway.

4. A structure provided with a hatchway, a closure for the hatchway, and a guard for the hatchway comprising a leaf, a second 100 leaf for folding against the first mentioned leaf, and spring hinges connecting the sections and connecting the first section with the closure and serving to swing the guard to an open position when the closure is 105 raised.

5. A structure provided with a hatchway, a closure for the hatchway, a guard for the hatchway having a plurality of sections, means for hingedly connecting one section with the closure and swinging the section outwardly when the closure is opened, and means for hingedly connecting the second section with the first section and swing-

ing the second section outwardly when the closure is opened.

In testimony whereof I affix my signature in presence of two witnesses.

Mrs. FLORA J. McACHRAN.

HALLIE C. DEUPREE,
MARY M. TINUS.
